CIRCUIT BREAKER

Oliver S. Jennings, Pittsburgh, Pa., assignor to Westinghouse Electric & Manufacturing Company, East Pittsburgh, Pa., a corporation of Pennsylvania

Application September 10, 1937, Serial No. 163,212

10 Claims. (Cl. 175—294)

The invention relates in general to circuit breakers and is particularly concerned with circuit breakers of the type used for controlling lighting and moderate power distribution feeder circuits.

An object of the invention is the provision of an improved circuit breaker which is operable to automatically open the circuit in response to an overload or abnormal condition and which will automatically reclose itself when, and only when, the condition causing the overload is removed or cleared from the controlled circuit.

Another object of the invention is the provision of a circuit breaker of the type mentioned which is simple and inexpensive to manufacture and which is safe and reliable in operation.

Another object of the invention is the provision of a circuit breaker of the above-mentioned type that is both manually operable and automatically operable to open and reclose the circuit.

The novel features that are considered characteristic of the invention are set forth in particular in the appended claims. The invention itself both as to structure and operation, together with additional objects and advantages thereof, will best be understood from the following description of several embodiments thereof when read in connection with the accompanying drawings, in which:

30 Figure 1 is a vertical sectional view of an automatic circuit breaker embodying the features of the invention, the various parts being shown in the positions they occupy when the breaker is closed;

35 Fig. 2 is a vertical sectional view of the circuit breaker, similar to Fig. 1, showing the parts in tripped open position following the occurrence of an overload of predetermined magnitude and duration;

40 Fig. 3 is a vertical sectional view of the circuit breaker, similar to Fig. 2, showing the position of the parts in the tripped open position following the occurrence of an overload, the latch means being shown in the operative position in which it prevents reclosing of the breaker;

45 Fig. 4 is a horizontal sectional view of the circuit breaker shown in Fig. 1, taken on the line IV—IV of Fig. 1;

50 Fig. 5 is a schematic diagram illustrating the electrical connection of the circuit breaker in the circuit which it controls;

55 Fig. 6 is a vertical sectional view of a modified form of automatic circuit breaker which includes means for manually opening and closing the contacts of the breaker;

Fig. 7 is a horizontal sectional view of the circuit breaker shown in Fig. 6, taken on the line VII—VII of Fig. 6, the electromagnetic latch means being omitted in order to simplify the figure; and

Fig. 8 is a schematic diagram illustrating a further modification of the invention.

The present invention constitutes a further development of the invention disclosed in my Patent No. 2,070,305, issued February 9, 1937, and assigned to the assignee of this invention.

The automatically reclosing circuit breaker illustrated in Figs. 1 through 5, inclusive, is of the same general construction as the circuit breaker shown in Figs. 1 through 6 and described in connection therewith in the aforementioned patent. In the present invention, however, there is provided in cooperative association with the breaker a novel means for preventing reclosing of the contacts of the breaker during the existence of the condition causing the overload.

Referring to Figs. 1 through 5, inclusive, the single-pole double-break circuit breaker illustrated comprises in general a recessed base 9, a pair of spaced stationary contacts 11, a pair of cooperating movable contacts 13, an actuating mechanism indicated generally at 15 which is operable in response to predetermined overload conditions to move the contacts 13 to open circuit position, and which is automatically operable after a predetermined time to return the movable contacts 13 to closed circuit position, and a means indicated generally at 17 for preventing reclosing of the contacts during the existence of the condition causing the overload.

The various parts of the circuit breaker are supported and enclosed by the base 9, which is of molded insulating material, and if desired, a cover 19, also of molded insulating material, may be provided for closing the open side of the base.

Two strips of conducting material 21 are supported on the base 9 by means of screws 23. A portion of each of these strips extends through the upstanding end wall of the base 9 in order to provide terminals for the breaker, suitable screws 25 being provided for connecting the line and load conductors thereto. The stationary contacts 11 are affixed to the inner ends of each of these conducting strips 21 by means of the screws 23.

The two movable contacts 13 are carried by a switch member consisting of a pair of U-shaped bimetallic control elements 27. Each of the bimetallic control elements 27 comprises a substantially flat strip of bimetallic material which

is looped back upon itself and which is provided with a pivot pin 29 affixed to the central portion of the loop. The movable contacts 13 are affixed to the ends of the lower legs of the control elements 27. The ends of the control elements opposite to the ends whereon the contacts 13 are supported are electrically and mechanically connected by means of a tie member 31, which comprises a flat strip of conducting material riveted to the ends of the elements 27.

The interconnected control elements 27 are pivotally supported upon two spaced upstanding members 33 of insulating material, each of which is provided with a suitable bearing portion for engaging one of the pivot pins 29 of the control elements 27. The support members 33 are secured to the base by means of suitable screws 35.

The bimetallic control elements 27 constitute a part of the actuating means of the circuit breaker which will now be described. In addition to the bimetallic control elements 27, the actuating means of the breaker includes a U-shaped pivot actuating member 37 and a pair of overcenter springs 39 which connect the free end 25 of the actuating member 37 to the tie member 31 of the bimetallic control elements. The actuating member 37 is substantially U-shaped and is pivotally supported on a U-shaped support 41 secured to the base by means of screws 43. The pivot ends of the actuating member 37 are provided with bearing portions 45 (Fig. 4) for engaging the pivot pins 29 carried by the support 41. The tie member 31 and the cross portion 49 of the actuating member 37 are provided with 35 openings which are engaged by the bent ends of the overcenter springs 39.

A bracket member 51, which is fastened to the base 9 by suitable means, is provided for defining the limits of motion of the actuating member 37, these limits being adjustable by means of set screws 53 and 55. The limit of motion of the switch member consisting of the control elements 27 in a counter-clockwise direction about their pivot pins 29 is defined by the engagement of the 45 moving contacts 13 with the stationary contacts 11, and the movement of the switch member in a clockwise direction is defined by the engagement of the upper side of the contact end of each of the bimetallic elements 27 with a projection 57 that extends inwardly from the end wall of the base 9.

The main circuit through the breaker extends from the line conductor strip 21, stationary contact 11, cooperating movable contact 13, the associated bimetallic control element 27, thence through the tie member 31, which connects the ends of the looped control elements, through the other looped control element 27 and its associated movable contact 13 to the opposite stationary contact 11 and thence through the second conducting strip 21 to the load.

It will be noted, as shown particularly in Fig. 4, that the space between the two bimetallic control elements 27 is entirely clear in order to permit free motion of the overcenter operating springs 39.

The circuit breaker thus far described is substantially the same as the automatic circuit breaker disclosed in the aforementioned Patent 70 No. 2,070,305. The operation of the breaker as thus far described is briefly as follows: When the breaker is in closed position, as shown in Fig. 1, and an overload of sufficient magnitude and duration occurs in the circuit controlled by the 75 breaker, the bimetallic control elements 27 are

heated sufficiently to move the tie member 31 in an upward direction away from the stationary contacts 11. So long as this movement does not bring the line of action of the overcenter springs 39 above the pivot axis 47 of the actuating member 37, the breaker will remain in closed circuit position. If, however, the overload is of sufficient magnitude and duration to cause the tie member to be moved a sufficient amount to change the line of action of the 10 springs 39 relative to the pivot axis 47, it is apparent that the circuit breaker is in an unstable position due to the fact that the overcenter springs 39 exert a component of force tending to bias the actuating member 37 in a counter-clockwise direction about its pivot axis 47. This component of force moves the actuating member from the position shown in Fig. 1 to that shown in Fig. 2. This movement once initiated progresses with increasing acceleration and 20 moves the line of action of the overcenter springs 39 above the pivot axis 29 of the switch member consisting of the control elements 27, thereby producing a component of force tending to move these elements in a clockwise direction about 25 their pivot. This results in the movement of the control elements 27 and the movable contacts carried thereby from the closed position shown in Fig. 1 to the open position shown in Fig. 2 with 30 a snap action.

In the absence of the means for preventing reclosing of the breaker, the actuating means automatically recloses the contacts in the following manner. After the bimetallic control elements 35 27 have cooled, these elements assume their normal condition shown in Fig. 1 causing the tie member 31 to be moved downwardly. The downward movement of the tie member 31 moves the line of action of overcenter springs 39 below the pivot axis 29 to effect movement of the control 40 elements 27 and movable contacts 13 from open to closed position with a snap action. The movement of the control elements 27 to closed position moves the line of action of the overcenter springs 39 below the pivot axis 47 of the actuating member, so that the springs effect clockwise movement of the actuating member 37 from the position shown in Fig. 2 back to the position shown in Fig. 1.

In the above description of the operation of 50 the breaker, it has been assumed that the movement of the bimetallic control elements 27 occurred in response to internal heating produced by the flow therethrough of an overload current. It is quite possible, however, to cause automatic 55 operation of the breaker to take place as a result of changes in the temperature of the medium surrounding the breaker. Thus if the circuit breaker is disposed within a transformer tank in such a manner that the bimetallic control elements are in contact with the oil used for insulating the transformer, the operation of the circuit breaker might result from a steady increase in the temperature of the oil. If the operation of the circuit breaker is affected by the heating 60 of the surrounding medium, the breaker will in most instances remain in open position for a considerable period of time due to the fact that the cooling of the large body of oil within the transformer tank takes place comparatively 70 slowly.

Referring now to the means indicated generally at 17 for preventing reclosing of the circuit breaker during the existence of the condition causing the overload. This means comprises in 75

general a pivoted latch 59 of magnetic material or at least having a portion of magnetic material to form an armature, an electromagnet 61 for moving the latch from released position to latching position when energized a predetermined amount, and a transformer 63 for energizing the electromagnet 61. The latch 59 is pivotally supported by means of a pivot pin 65 projecting from the side wall of the base 9 and is biased to an inoperative released position by means of a coiled compression spring 67 a portion of which extends within a bore provided in the core of the electromagnet 61. One end of the spring engages a projection provided on the latch 59, while the other end of the spring engages an adjusting screw 69 which serves as an adjusting means for adjusting the amount of current required to move the latch from released to latching position.

The electromagnet 61 comprises a core 71 and a winding 73. The electromagnet is supported by an angle bracket 75 of magnetic material which is secured to one of the side walls of the base 9. The horizontal portion 77 of the bracket 75 serves to support a pair of spaced contacts 79 and 81, which are insulated from the bracket 75 by means of insulating spacer plates 83. The contacts 79 and 81 are adapted to be bridged to complete a circuit for the winding 73 of the electromagnet 61 when the breaker is in open position, by means of a bridging plate 85 of conducting material which is secured to the tie member 31 and insulated therefrom by means of an insulating plate 87, the bridging plate 85 being disposed between the ends of the springs 39, as best shown in Fig. 4.

The transformer 63 is mounted on the base 9 on any suitable location, and comprises a core 89, a primary winding 91 and a secondary winding 93 (Fig. 5). The internal electrical connections of the electromagnet 61, the contact means 79, 81, 85 and the transformer 63 are illustrated in the schematic diagram shown in Fig. 5. The primary winding 91 of the transformer 63 is connected in shunt relation across the contacts 45 of the breaker by means of conductors 95 and 97, one terminal of the winding 91 being connected by the conductor 95 to the line conductor strip 21, and the other terminal of the primary winding being connected by conductor 97 to the load conductor strip 21. One terminal of the secondary winding 93 of the transformer 63 is connected to one end of the winding of the electromagnet 61 by means of a conductor 99, the opposite terminal of the winding 93 being connected to the return wire 101 by means of a conductor 103. The opposite end of the winding 73 of the electromagnet 61 is electrically connected to the contact 81 by means of a conductor 105, while the other contact 79 carried by the bracket 75 is connected to the load conductor strip 21 by means of a conductor 107. It will thus be seen that the primary winding 91 of the transformer 63 is shunted by the contact means 65 of the breaker when the breaker is in closed circuit position, so that the transformer is substantially deenergized under these conditions. It will also be seen that the electromagnet 61 is adapted to be automatically connected by means of the contacts 79, 81, 85 in series circuit with the secondary 93 of the transformer 63 and directly across the load and in series therewith when the breaker is in open circuit position.

The operation of the means for preventing re-closing of the contacts of the breaker is briefly

as follows: With the circuit breaker in closed position, as shown in Fig. 1, the transformer 63 is shunted by the breaker contacts, so that it is substantially deenergized and no current flows through the electromagnet 61. Thus the latch 59 is maintained by the spring 67 in inoperative or released position. When an overload in the circuit controlled by the breaker occurs, the switch member and movable contacts 13 are automatically moved to the open circuit position 10 in the manner previously described as a result of the flexing of the bimetallic control elements 27. When the movable contacts 13 separate from the stationary contacts 11 and the arc is extinguished, current flows through the primary of 15 the transformer 63 since it is no longer shunted by the contact means of the breaker. This materially reduces the flow of current to the load so as to protect the circuit and load apparatus. When the switch member and movable contacts 20 13 have reached their full open circuit position, the bridging plate 85 bridges the stationary contacts 79 and 81 to complete a circuit for the electromagnet 61 which connects the electromagnet 61 in series circuit with the secondary winding 25 93 of the transformer 63 and the load. Since the transformer 63 is energized due to the opening of the main contacts of the breaker, the electromagnet 61 is now energized an amount depending upon the impedance of the load since it is 30 in series therewith. If the impedance of the load is below a predetermined amount, that is to say, if the condition causing the overload still exists, the electromagnet 61 is energized a sufficient amount by the current flowing through its winding 35 to move the latch from its inoperative or released position, as shown in Fig. 2, to latched position, as shown in Fig. 3, in which it engages the tie member 31 connecting the bimetallic control elements 27 to hold these elements in open 40 circuit position. Under these conditions, the switch member and the movable contacts 13 are held latched in open position to prevent reclosing of the circuit breaker. The circuit breaker cannot be reclosed by the actuating mechanism 45 until the impedance of the load is increased as by reducing the magnitude of the load to a value substantially equal to or less than a safe normal full load value, or until the fault condition causing the overload is corrected or cleared. When 50 this is done, the pull of the electromagnet 61 is reduced because of the reduction in the current flowing through its winding so that the force exerted by the biasing spring 67 is sufficient to move the latch to its inoperative or released position, as shown in Fig. 2 to release the switch member. The actuating mechanism is now free to automatically reclose the circuit breaker. 55

When the latch 59 releases the tie member 31, the bimetallic control elements 27 which have cooled a sufficient amount, move the line of action of the overcenter springs 39 below the pivoted axis 29 of the control elements 27 to effect automatic reclosing of the circuit breaker in the 60 manner previously described.

The adjusting screw 69 forms a simple adjusting means for adjusting the amount of current required to cause the electromagnet to move the latch from inoperative to latching position so 70 that the lock-out means 17 may be adjusted to operate under different predetermined circuit conditions.

The magnetic circuit of the electromagnet 61 is so designed that the latch 59 will be moved to its 75

inoperative or released position at current values slightly below the current value necessary to effect movement of the latch to its latching position. This particular feature can be carried out in any number of ways, one way being to have a very small air gap between the armature portion of the latch 59 and the core 71 of the electromagnet.

A modification of the invention is illustrated in Figs. 6 and 7. The structure of the circuit breaker in this modification is substantially similar to the previously described circuit breaker and to the embodiment shown and described in connection with Figs. 8 and 11 of the aforementioned Patent No. 2,070,305. In this modification, the circuit breaker is provided with a manual operating means for opening and closing the breaker. Since the basic structure is substantially similar to the device previously described, the same reference characters will be used wherever applicable.

The circuit breaker illustrated in Figs. 6 and 7 comprises in general a recessed base 9 of molded insulating material, a pair of stationary contacts 11, a pair of cooperating movable contacts 13, an actuating means indicated generally at 37, a means indicated generally at 17 for preventing reclosing of the circuit breaker during the existence of the condition causing an overload, and a manual operating means indicated generally at 109.

The stationary contacts 11 are secured to a pair of terminal conducting strips 21 which are in turn secured to the base 9 by means of screws 23.

The movable contacts 13 are carried by a switch member consisting of a pair of U-shaped bimetallic control elements 27, the upper ends of which are mechanically and electrically connected together by means of a tie member 31 of conducting material. The control elements 27 are provided with pivot pins 29 for pivotally mounting the elements on a pair of spaced supporting members 33 of insulating material.

The bimetallic control elements 27 form a part of the actuating means which will now be briefly described. The actuating means for the breaker includes the bimetallic control elements 27, a U-shaped actuating member 37 pivoted at 47 on a support 41, a pair of overcenter springs 39 connecting the free end portion 49 of the actuating member 37 to the tie member 31.

The movement of the switch member consisting of the bimetallic control elements 27 and the movable contacts 13 in a clockwise direction about their pivot axis is limited by an inwardly extending projection 57 formed on the end wall of the base 9.

A bracket member 51 is provided for defining the limits of movement of the actuating member 37, these limits being adjustable by means of set screws 53 and 55.

The means 17 for preventing reclosure of the circuit breaker is identical to the corresponding means of the previously described device, and comprises generally a pivoted magnetic latch 59 biased to released or inoperative position by a spring 67, an electromagnet 61 for moving the latch from released to latching position when energized a predetermined amount, and a transformer indicated generally at 63 for energizing the electromagnet 61. The electromagnet 61 is provided with an adjusting screw 69 which serves as an adjusting means for determining the amount of current required to move the latch from inoperative to latched position. A pair of stationary contacts 79 and 81 are supported by

the bracket 75 which supports the electromagnet 61 and insulated therefrom by the insulating plates 83. These contacts 79 and 81 are adapted to be bridged by a bridging plate 85 of conducting material which is secured to the tie member 31 and insulated therefrom by an insulating plate 87. The contact means consisting of the bridging plate 85 and the spaced contacts 79 and 81 is adapted to close the circuit to the electromagnet 61 when the circuit breaker is in open circuit position to connect the electromagnet 61 in series circuit with the secondary of the transformer 63 and the load the same as in the previously described device. The primary winding of the transformer is connected in shunt relation across the contact means of the breaker.

In this modification of the invention, the circuit breaker is provided with a manual means indicated generally at 109 for manually opening and closing the contacts of the breaker. The manual means 109 comprises in general a bifurcated operating member 111 which straddles the actuating mechanism and which is pivotally supported by means of pivot pins 113 on the support 41, an operating handle 115 secured to the bight portion of the operating member 111 and a pair of depending projections 117 and 118 formed integral with the bight portion of the operating member 111. The handle 115 projects through an opening 121 provided therefor in the cover 123 of the base, and has a closure portion 125 which acts to close the opening in any position of the handle.

The actuating member 37 of the actuating means of the circuit breaker is provided with a Y-shaped coupling member 127, the legs of which are secured to the legs of the actuating member 37 by means of rivets 129 (Fig. 7). The upper end 131 of the Y-shaped coupling member 127 is disposed between the depending projections 117 and 118 of the operating member 111 for engagement thereby when the operating handle 115 is moved.

The spacing of the projections 117 and 118 is such that they permit the actuating member 37 to be moved independently of the operating handle during automatic operation of the actuating means when the handle is in closed circuit position.

A manually operable latch 133 is pivotally mounted on one of the side walls of the base 9 by means of a pivot pin 135. The latch 133 is provided with a latch recess 137 for engaging a latch pin 139 which is secured to one of the legs of the bifurcated operating member 111. The latch 133 is also provided with a projecting member 141 of insulating material which extends through a slotted opening 143 in one of the side walls of the base 9. This member 141 permits the latching member 133 to be moved so as to disengage the operating handle and permit manual operation of the breaker. The latch 133 is biased by a spring 144 (Fig. 7) towards latching position so as to latch the operating member 111 when the same is moved to closed circuit position.

The circuit breaker is shown in the closed circuit position in Fig. 6. It will be noted that the latch 133 through engagement of the latch recess 137 with the pin 139 holds the operating member 111 in closed circuit position. If it is desired to manually open the breaker, the latch 133 is lifted by means of the insulating projection 141 and the handle is moved in a counter-clockwise direction. During this movement, the projection 75

117 engages the upper end 131 of the Y-shaped coupling member 127 and moves that member and through it the actuating member 37 a sufficient distance to cause the line of action of the 5 overcenter springs 39 to move above the pivot axis 47 of the actuating member 37. The end 131 of the coupling member 127 then disengages the projection 117 and moves with the actuating member 37 to which it is secured, under the biasing action of the overcenter springs 39 to open circuit position. In moving to this position, the line of action of the overcenter springs 39 is carried across and above the pivot axis 29 of the bimetallic control elements 27, and these members together with the movable contacts carried thereby move to open circuit position with a snap action.

In manually closing the circuit breaker, substantially the reverse action takes place. The 20 operating handle 115 is moved in a clockwise direction about its pivot 113 to close the contacts of the breaker. During this movement, the depending projection 118 engages the upper end 131 of the coupling member and moves that 25 member together with the actuating member 37 to which it is secured in a clockwise direction about the pivot axis 47 to the closed circuit position shown in Fig. 6. During this movement, the upper end of the coupling member 127 disengages the projection 118, and the line of action of the overcenter springs first crosses the pivot axis 29 of the bimetallic control elements to effect 30 movement of the control elements 27 and the movable contacts 13 to closed circuit position 35 with a snap action, and then crosses the pivot axis 47 of the actuating member 37 to effect movement of that member to closed position shown in Fig. 6.

Both the opening and the closing operations 40 once initiated by the operating handle take place substantially instantaneously and with increasing acceleration as soon as the line of action of the overcenter springs 39 crosses either of the pivot axes 29 or 47.

45 As has previously been pointed out, the spacing of the projections 117 and 118 is such as to permit automatic operation of the actuating means 15 when the handle is held latched in closed position.

50 The automatic operation of the actuating means is identical to the automatic operation of the device shown in Figs. 1 to 4 and previously described in connection therewith. Briefly, when the breaker is in closed position, the handle being held latched in closed position, as shown in Fig. 6, and a predetermined overload or increase in temperature of the ambient medium occurs, the bimetallic control elements 27 expand in such a manner that the tie member 31 is moved upwardly. This upward movement of the tie member carries the line of action of the springs 39 above the pivot axis 47 of the actuating member 37, and the springs will exert a component biasing that member in a counter-clockwise direction. The immediate result is to cause the actuating member 37 to move in a counter-clockwise direction, the limit of motion being defined by the engagement of the upper end 131 of the coupling member 127 with the depending projection 118 of the operating member 111. As the actuating member 37 moves in a counter-clockwise direction, as described above, the line of action of the springs 39 is carried across and above the pivot axis 29 of the connected bimetallic control elements, thereby causing those

elements and the movable contacts 13 carried thereby to be moved from closed to open circuit position with a snap action.

In the absence of the lock-out means 17, the actuating means effects automatic reclosure of 5 the contacts in the following manner: As the bimetallic control elements 27 cool following automatic opening of the contacts, the tie member 31 and with it the line of action of the overcenter springs 39 is moved downwardly. As soon 10 as the line of action of the springs crosses the pivot axis 29 of the connected control elements, these elements and the movable contacts 13 carried thereby are moved to closed circuit position with a snap action. As this movement progresses, the line of action of the overcenter springs 39 also crosses the pivot axis 47 of the actuating member 37 to cause clockwise movement of that member to the position shown in Fig. 6. 15

20 The depending projections 117 and 118, which provide opposed surfaces for engaging the coupling member 127, comprise in effect a lost motion connection between the operating handle and the actuating means. Thus, even though 25 the handle is held in closed circuit position, as shown in Fig. 6, either manually or through the agency of the latch 133, the breaker will open automatically upon the occurrence of an overload. The breaker is thus entirely trip-free of 30 the operating handle.

35 The latch controlling electromagnet 61 and the transformer 63 are electrically connected in the same manner as in the embodiment shown in Figs. 1 through 5 and described in connection therewith. The primary of the transformer 63 is connected in shunt relation to the main contacts of the breaker, and the secondary winding of the transformer is connected in series circuit with the electromagnet 61 and the load when 40 the breaker is in open circuit position by means of the contacts 79, 81, 85, as previously described in connection with Fig. 5.

45 The operation of the lock-out means indicated generally at 17 is substantially identical with the corresponding means described in connection with Figs. 1 through 5. The transformer 63 becomes energized when the breaker opens, and the electromagnet 61 is connected in series circuit with the secondary of the transformer and with 50 the load by the closing of the contact means 79, 81, 85 when the breaker reaches full open circuit position. If the impedance of the load is below a predetermined value, the current flow through the electromagnet is sufficient to move 55 the latch 59 from inoperative to latched position, in which last position it latches the switch member consisting of the bimetallic control elements 27 and the movable contacts 13 in open circuit position, so that the breaker cannot be reclosed 60 until the fault condition is cleared or the impedance of the load is increased, as, for example, by removal of part of the load apparatus from the circuit. When the impedance of the load circuit is increased above the predetermined 65 value, or the fault condition is cleared, the pull of the electromagnet 61 becomes insufficient to hold the latch 59 in its latching position, and the spring 67 moves the latch to its inoperative position, as shown in Fig. 6, to effect release of the 70 switch member. Following release of the switch member, the actuating means automatically recloses the circuit breaker in a manner previously described.

In order that the transformer 63 will not be 75

energized when the breaker is manually opened by means of the operating handle 115, a cut-out switch indicated generally at 147 is provided which opens the circuit to the primary of the transformer when the operating handle 115 is moved to open position to open the breaker. The plunger 149 of the cut-out switch is moved downwardly to open the switch by a projection 151 formed at the lower end of one of the legs of the operating member 111. This projection 151 moves the plunger 149 downwardly to open the switch 147 when the operating handle 115 is moved to open position. The contact means of the cut-out switch 147 are adapted to be connected in the conductor 95 leading to the primary 91 of the transformer, as indicated by the alternative dotted lines 153 in Fig. 5.

A further modification of the invention is illustrated schematically in Fig. 8. In this modification, the circuit breaker and its actuating means are identical to that shown and described in connection with Figs. 1 through 4. The breaker operates automatically in the same manner as the previously described breaker and the same reference characters have been used wherever applicable. An impedance 161 in the form of a resistance has been substituted in this modification in place of the transformer used in the previously described device. The latch 59 for holding the movable contacts in open circuit position in this modification is biased by the spring 67 to its latching position, and the electromagnet 61 when energized a sufficient amount moves the latch to its inoperative or released position. The impedance 161 is connected in shunt circuit relationship to the contact means of the breaker and a resistance 163 is connected in series circuit with the latch controlling electromagnet 61. It will be noted that when the circuit breaker is in open circuit position, the contacts 79, 85, which may take the form of the contact means 79, 81, 85 shown in Figs. 1 through 4, connect the electromagnet 61 in parallel with the load 165, the circuit for the electromagnet and the load circuit being connected in series with the impedance 161.

The operation of this modification of the invention is briefly as follows: When the circuit breaker is opened in response to predetermined overload conditions, the electromagnet 61 is connected in parallel with the load by means of the contacts 79, 85. If the impedance of the load is below a predetermined value, insufficient current will flow through the electromagnet 61 to move the latch to inoperative position, and the movable contacts will be held in open circuit position by means of the latch 59, so that the breaker is prevented from being automatically reclosed. When the impedance of the load circuit is increased above the predetermined value, as by removing a part of the load from the circuit or by correcting the fault condition causing the overload, sufficient current will flow through the electromagnet 61 to move the latch 59 to its inoperative or released position. The actuating means of the circuit breaker is now free to reclose the contacts of the breaker in the manner previously described in connection with the embodiment shown in Figs. 1 through 4.

It will thus be seen that the invention provides an improved automatically reclosing circuit breaker embodying a novel means for preventing reclosing of the contacts of the breaker during the existence of the condition causing the overload, the means for preventing reclosing of the contacts being automatically rendered inop-

erative to prevent reclosure when the fault condition is cleared.

While the invention has been disclosed in accordance with the provisions of the statutes, it is to be understood that various changes in the structural details thereof may be made without departing from the spirit of the invention. It is desired, therefore, that the appended claims be given the broadest reasonable construction permissible in the light of the prior art. 10

I claim as my invention:

1. In a circuit breaker for controlling a load circuit, relatively movable contacts, actuating means including an overcenter spring for opening and closing said contacts and an electro-responsive element operable in response to predetermined overload conditions to cause said spring to automatically open said contacts and operable to cause said spring to automatically reclose said contacts following automatic opening thereof, means operable upon automatic opening of said contacts for preventing reclosing of said contacts during the existence of the condition causing the overload, said means comprising a latch normally biased to released position and movable to a latching position to hold said contacts open, an electromagnet for moving said latch to latching position when energized a predetermined amount, a transformer the primary of which is connected in shunt relation to said contacts and the secondary of which is connected in series with said electromagnet, and means for automatically connecting said transformer secondary and said electromagnet in shunt relation to the load when said contacts are automatically opened, the magnetic circuit of said electromagnet being such that its reluctance is changed only a relatively small amount by the movement of said latch to latching position so as to permit return of said latch to released position when the current flowing through said electromagnet is decreased to a value only slightly below the value required to cause said latch to be moved to latching position. 30

2. In a circuit interrupter for controlling a load circuit, relatively movable contacts, an overcenter spring for opening and closing said contacts, an electro-responsive control element operable in response to predetermined conditions to cause said spring to automatically open said contacts and for causing said spring to automatically reclose said contacts after an interval of time following said automatic opening operation, means operable upon automatic opening of said contacts for preventing reclosing of said contacts until the predetermined conditions have ceased to exist, said means comprising a latch operable to latch said contacts open, and an electromagnet acting directly on said latch for controlling the latch, means electrically connecting said electromagnet in shunt relation to the load circuit when said contacts are automatically opened, and an impedance connected in shunt relation to said contacts, said electromagnet causing said latch to release said contacts for closing immediately upon cessation of said predetermined conditions. 55

3. In a circuit interrupter for controlling a load circuit, relatively movable contacts, an overcenter spring for opening and closing said contacts, an electro-responsive control element operable in response to predetermined conditions to cause said spring to automatically open said contacts and for causing said spring to automatically reclose said contacts after an interval of time fol- 70

lowing said automatic opening operation, means operable upon automatic opening of said contacts for preventing reclosing of said contacts during the existence of said predetermined conditions, 5 said means comprising a latch operable to latch said contacts open, an electromagnet acting directly on said latch for controlling said latch, means for automatically electrically connecting said electromagnet in shunt with the load upon automatic opening of said contacts, and an impedance connected in circuit with the load upon automatic opening of said contacts, said electromagnet causing said latch to free said contacts for closing immediately upon cessation of said predetermined conditions. 10

4. In a circuit breaker for controlling a load circuit, relatively movable contacts, actuating means including an overcenter spring for opening and closing said contacts and an electro-responsive control element operable in response to predetermined overload conditions to cause said spring to automatically open said contacts and for causing said spring to automatically reclose said contacts after a time interval following said automatic opening operation, means operable upon automatic opening of said contacts for preventing reclosing of said contacts if the impedance of the load circuit is below a predetermined value, said means comprising a latch operable to latch said contacts open, an electromagnet acting directly on said latch for controlling said latch, means electrically connecting said electromagnet in shunt relation to the load upon automatic opening of said contacts, and an impedance connected in series with the load upon automatic opening of said contacts, said electromagnet being operable to cause said latch to free said contacts for reclosing immediately upon cessation of the conditions causing the overload. 15

5. In a circuit breaker for controlling a load circuit, relatively movable contacts, actuating means including an overcenter spring for opening and closing said contacts and an electro-responsive control element operable in response to predetermined overload conditions to cause said spring to automatically open said contacts and for causing said spring to automatically reclose said contacts after a time interval following said automatic opening operation, means operable upon automatic opening of said contacts for preventing reclosing of said contacts if the impedance of the load circuit is below a predetermined value, said means comprising a latch operable to latch said contacts open, an electromagnet for controlling said latch, and a transformer the secondary of which is connected in circuit with said electromagnet and together with the electromagnet in shunt to the load upon automatic opening of said contacts, the primary of said transformer being connected in shunt to the contacts. 20

6. In a circuit interrupter for controlling a load circuit, relatively movable contacts, an overcenter spring for opening and closing said contacts, an electro-responsive control element operable in response to predetermined conditions to cause said spring to automatically open said contacts and for causing said spring to automatically reclose said contacts after an interval of time following said automatic opening operation, means operable upon automatic opening of said contacts for preventing reclosing of said contacts until the predetermined conditions have ceased to exist, said means comprising a latch operable to latch said contacts open, and an electromagnet for controlling the latch, and a transformer hav- 25

ing its secondary connected in circuit with the electromagnet and its primary connected in shunt relation to said contacts, the secondary of the transformer and the connected electromagnet being connected in shunt to the load upon automatic opening of said contacts. 5

7. In a circuit breaker for controlling a load circuit, relatively movable contacts, actuating means including an overcenter spring for opening and closing said contacts, and an electro-responsive control element operable in response to predetermined overload conditions to cause said spring to automatically open said contacts, and for causing said spring to automatically reclose said contacts after an interval of time following said automatic opening operation, means operable upon automatic opening of said contacts for preventing reclosing of said contacts during the existence of the condition causing the overload, said means comprising a latch operable to latch said contacts open, an electromagnet acting directly on said latch for controlling said latch, means for automatically connecting said electromagnet in shunt relation to the load when the contacts are automatically opened, and an impedance connected in shunt relation to said contacts, said electromagnet being operable to cause said latch to release said contacts for reclosing immediately upon cessation of the condition causing said overload. 10

8. In a circuit breaker for controlling a load circuit, relatively movable contacts, actuating means including an overcenter spring for opening and closing said contacts and an electro-responsive element operable in response to predetermined overload conditions to cause said spring to automatically open said contacts and operable to cause said spring to automatically reclose said contacts following automatic opening thereof, means operable upon automatic opening of said contacts for preventing reclosing of said contacts during the existence of the condition causing the overload, said means comprising a latch normally biased to a released position and movable to a latching position to latch said contacts open, an electromagnet for moving said latch to latching position when energized a predetermined amount, a transformer the primary of which is connected in shunt relation to said contacts and the secondary of which is connected in series with said electromagnet, means for automatically connecting said transformer secondary and said electromagnet in shunt relation to the load when said contacts are automatically opened, the magnetic circuit of said electromagnet being such that its reluctance is changed only a relatively small amount by the movement of said latch to latching position so as to permit return of said latch to released position when the current flowing through said electromagnet is decreased to a value only slightly below the value required to cause said latch to be moved to latching position, and adjusting means for varying the value of current required to cause said electromagnet to move said latch to latching position. 15

9. In a circuit breaker, relatively movable contacts, actuating means automatically operable in response to predetermined conditions to open said contacts and to thereafter reclose said contacts, a manual operating handle movable to cause opening or closing of said contacts, an impedance connected at all times in shunt relation to said contacts, means operable upon automatic opening of said contacts for preventing reclosing of said contacts as long as said predetermined 20

condition exists, and means operable by opening movement of the manual operating handle for opening the circuit to interrupt the flow of current.

- 5 10. A circuit breaker for controlling a load circuit comprising relatively movable contacts, actuating means including an overcenter spring for opening and closing said contacts, an electro-responsive element operable to cause said spring to 5 automatically open said contacts in response to predetermined overload conditions and for causing said spring to automatically reclose said contacts

10 after automatic opening thereof, a manually operable handle operable to open and to close said contacts, an impedance connected in shunt to said contacts, and electromagnetic means operable upon automatic opening of said contacts to prevent reclosing of said contacts as long as the impedance of the load circuit is below a predetermined value, and an additional pair of contacts in the circuit opened by opening movement of said manual operating handle for interrupting 10 the flow of current in the circuit.

OLIVER S. JENNINGS.
